Specification for Design.

Patented Mar. 3, 1914.

Application filed September 29, 1913. Serial No. 792,520. Term of patent 14 years.

To all whom it may concern:

Be it known that I, ARTHUR E. LONGSHAW, a subject of the King of Great Britain and Ireland, residing at Salt Lake City and county of Salt Lake and State of Utah, have invented a new, original, and ornamental Design for Plaques, of which the following is a specification, reference being had to the accompanying drawings, forming part thereof.

The figure is a plan view of a plaque showing my new design.

I claim—

The ornamental design for a plaque as herein shown.

In testimony whereof I have signed my name to this specification in the presence of two subscribing witnesses.

ARTHUR E. LONGSHAW.
